ELECTRIC RECEPTACLE SUPPORT

William Sidney Adelman, Chicago, Ill.

Application April 17, 1937, Serial No. 137,428

2 Claims. (Cl. 173—338)

This invention is related to a supporting device for electric receptacles, and particularly to a device, which may be readily movable from one place to another.

One object of the present invention is to provide a receptacle supporting device, which may be conveniently positioned in various locations around the walls of a room without in any way puncturing, defacing or otherwise marring the walls or interior trim of the building structure.

Another object of the invention is to provide a receptacle supporting device, which may be readily changed from place to place without leaving unsightly marks in or on walls or the like.

Another object of the invention is to provide a novel construction and arrangement whereby a supporting device of the character described may be readily, conveniently and quickly positioned in or around any desired part of a room, or the like, by inserting a portion of the support between portions of the building construction as, for example, between the wall and portions of the interior trim such as baseboards, door and window casings, or the like.

A further object of the invention is to provide a support of the character described, which is of simple construction, efficient in its operation and economical to manufacture.

A still further object of the invention is to improve devices of the character described in sundry details hereinafter referred to and particularly pointed out in the appended claims.

One embodiment of the present invention is shown for illustrative purposes in the accompanying drawing, in which:

Fig. 1 is an elevational view of a portion of a wall having parts thereof broken away, and illustrating the application or mounting of my improved receptacle support with reference thereto;

Fig. 2 is an enlarged elevational face view of my improved receptacle support showing an electric receptacle secured thereto, and illustrating the manner of mounting the receptacle support between a wall and baseboard; and

Fig. 3 is an elongated sectional elevational view of the structure illustrated in Fig. 2, and taken substantially as indicated by the line 3—3 thereof.

The illustrative embodiment of the present invention shown in the drawing comprises an electric receptacle support indicated, as a whole, by the numeral 5 and formed of suitable material such, for example, as metal, "Bakelite", hard rubber, or the like, the support 5 being shown, in the present instance, as comprising an elongated

substantially flat metal plate having a body portion 6 provided with a substantially arcuate end portion 7, and having a screw-threaded aperture 8 formed therein adjacent the central portion of the body 6.

Mounted on the body portion 6 adjacent one face thereof is an electric receptacle indicated, as a whole, by the numeral 9, and having an elongated opening 11 extending therethrough adapted to receive a bolt 12, preferably, in a manner to rotate thereon, said bolt having a screw-threaded end portion 13 engageable with the aperture 8 of the body portion 6, and having a head portion 14 adapted to cooperate with a shoulder 15 adjacent the opening 11 for securing the receptacle 9 in operative position with respect to the body portion 6.

It will be noted by reference to Fig. 2 that the receptacle 9 is provided with a plurality of conductor outlets or openings 16, and in order that these openings may be readily moved to various positions as may be desired, the arrangement illustrated in Fig. 3 contemplates the use of a resilient member or spring 17 positioned between the head 14 of the bolt 12 and the shoulder 15 of the receptacle for yieldingly holding the receptacle against the body member 6 of the support, thereby providing a structure whereby the receptacle 9 may be rotated about the bolt 12 without disturbing the connection of the bolt with the body portion 6, and to permit the positioning of the outlets or openings 16 at various angles according to the position of conductors 18 leading into the receptacle.

The support 5 is also provided with a holding portion 19 extending laterally from the body portion 6 and receptacle 9, and is provided with tapering side edges 21 as clearly illustrated in Figs. 1 and 2, the lower end of the holding portion 19 being provided with a tapering knife edge portion 22 to facilitate the positioning of the portion 19 between the face A of a wall and a baseboard B, for example, in the manner clearly illustrated in Fig. 3, the portion 19 being provided with a plurality of spring fingers 23 preferably adjacent its edges thereof, and shown, in the present instance, as being struck up from the portion 19 and bent laterally from the plane thereof in a manner to provide a wieldable binding action between the wall A and baseboard B for securing the support 5 and receptacle 9 mounted thereon against accidental displacement.

To facilitate the insertion of the holding portion 19 between a wall A and baseboard B, or other interior trim, and in a manner to position

the receptacle 9 as may be desired, the body member 6 is provided at one edge thereof preferably opposite the holding portion 19 with a wear piece 24 extending laterally from the plane of the support in a manner to overlie a portion of the receptacle 9, thereby providing means against which a force may be exerted to position the portion 19 between the wall and baseboard without causing a strain on the connection between the receptacle 9 and the body portion 6 of the support.

It will be observed from the foregoing description that the present invention provides a novel construction and arrangement whereby an electric receptacle may be conveniently positioned at various places in a room without defacing or otherwise marring the interior trim thereof, and that the receptacle may be readily and conveniently changed from one location to another as may be found desirable.

Obviously, the present invention is not limited to the precise construction and arrangement shown and described as the same may be variously modified. Moreover, all the features of the invention need not be used conjointly as the same may be used to advantage in variously different combinations and subcombinations.

What I claim as new and desire to secure by Letters Patent is:

30. 1. A device of the class described and in combination, an electric receptacle, a relatively thin

substantially flat support therefor, said support having a portion extending a substantial distance laterally at one side of said receptacle and adapted to be positioned between the wall and interior trim of a building, and a spring finger on 5 said laterally extending portion and offset from the plane thereof.

2. A device of the class described and in combination, an electric receptacle having an elongated opening extending therethrough and having a shoulder adjacent said opening, a relatively thin substantially flat support comprising a body portion having a screw-threaded aperture formed therein and a holding portion having tapering side edges extending laterally from said body 15 portion at one side thereof and adapted to be positioned between the wall and interior trim of a building, resilient spring fingers formed on said holding portion adjacent the respective edges thereof, a bolt having a head and a threaded portion operatively related to said shoulder and threaded aperture, respectively, for securing said receptacle to one side of said body portion, a resilient member positioned between said bolt head and shoulder, and a wear piece on said body portion at the opposite side thereof from said holding portion and extending laterally from the plane of 20 said support in a manner to overlie a portion of said receptacle.

30. WILLIAM SIDNEY ADELMAN.
